CLAIM

The ornamental design for a charging stand for tablet PC, as shown and described.

DESCRIPTION

FIG. 1 is a front view of a charging stand for tablet PC;
 FIG. 2 is a rear view thereof;
 FIG. 3 is a left side view thereof;
 FIG. 4 is a right side view thereof;
 FIG. 5 is a top view thereof;
 FIG. 6 is a bottom view thereof;
 FIG. 7 is a rear perspective view of the charging stand for tablet PC;
 FIG. 8 is a first perspective view of the charging stand for tablet PC in a first expanded state;
 FIG. 9 is a second perspective view of the charging stand for tablet PC in the first expanded state; and,
 FIG. 10 is a perspective view of the charging stand for tablet PC in a second expanded state.

The broken lines in the figures depict portions of the charging stand for tablet PC that form no part of the claimed design.
